AIR SEPARATOR

Thomas J. Sturtevant, Wellesley, Mass., assignor
to Sturtevant Mill Company, Boston, Mass., a
corporation of Massachusetts

Application July 18, 1940, Serial No. 346,184

6 Claims. (Cl. 209—144)

This invention relates to an air separator and more particularly to that type of air separator in which a rotary rejector fan is stationed within the separating chamber below a top outlet opening so as to sweep or cast out relatively coarse or oversized particles from a stream of air being drawn upwardly from the chamber through the outlet opening.

In a separator of the foregoing type, a small clearance or space usually occurs between the upper end of the rejector fan and the top cover of the separating chamber; and, inasmuch as it is difficult, especially by reason of the high speed of the fan, to seal or close off such clearance, there is opportunity for oversized or undesirably coarse particles to leak through such clearance into the outlet opening and thus to appear in the finished or separated product emerging from said opening. The entry of oversized or relatively coarse particles into the outlet opening is fostered in actual practice by the greater degree of suction in the outlet opening than in the separating chamber and, accordingly, by a positive flow of air from the chamber through the clearance into the outlet opening.

In accordance with the present invention, greater selectivity or sharpness of separation is accomplished in an air separator of the foregoing type by causing flow of air through the clearance between the upper end of the fan and the top cover of the separating chamber in a direction into the separating chamber while the stream of air carrying particles is passing into the space swept by the rejector fan. There are various expedients by which such desired flow of air through the clearance may be induced. For instance, it is possible to do so by opening the clearance to the outside atmosphere, in which case air from the atmosphere may be sucked into both the separating chamber and/or the outlet opening while the separator is in operation. Again, it is possible to provide the rejector fan at a region neighboring the clearance with auxiliary vanes that create a suctional current localized essentially at the clearance and serving to draw air from the outlet opening through the clearance into the separating chamber.

With the foregoing and other features and objects in view, the present invention will now be described in further detail with particular reference to the accompanying drawings, wherein—

Fig. 1 is a largely vertical sectional view through an air separator embodying the present invention as assembled with auxiliary apparatus shown in elevation.

Fig. 2 is an enlarged similar view through the rejector fan portion.

Fig. 3 represents a vertical section through the rejector fan portion of a modified form of the invention.

Fig. 4 is a similar view of still another form of the present invention.

Fig. 5 is a composite half section through the rejector fan on the line 5—5 of Fig. 3 and a half top plan view of said fan.

As shown in Fig. 1, the separating chamber 4 of the air separator hereof may be defined by a casing 10 whose upper portion may be essentially cylindrical and whose lower portion may be funnel-shaped. The pulverulent or particulate material to be air-separated or classified may be fed into the lower end portion of the chamber by a worm-feed conveyor 11 driven as by a pulley 12. The feed hopper 11a of the conveyor may be located outside of the separating chamber and its discharge end 11b may be arranged centrally somewhat above the air-inlet 14 near the lower end of the chamber so that the rising air currents may suspend therein and carry upwardly therewith the particulate material to be subjected to the separating or classifying action of the rejector fan. A discharge door 15 at the lower end of the chamber 9 makes possible periodic discharge, as desired, of the rejected relatively coarse particles or tailings.

The top of the separating chamber is closed off by a cover 16 through which there is a central outlet opening 17. Immediately above the top cover is a cylindrical chamber 18 for housing a main rotary fan 19, which generates an upward draft or surge of air through the separating chamber 4 whose outlet 17 opens directly into the chamber 18 through its bottom plate 9. Vanes or blades 19a of the main fan 19 are supported by arms 20 projecting radially from a hub 21, which is keyed to a vertical shaft 22 extending axially through the fan chamber 18 and thence downwardly through the opening 17 into the separating chamber. The bottom plate 9 of the main fan chamber 18 is shown as comprising an annular flange 9a projecting downwardly at a narrow clearance past the inner marginal edge 16a of the cover 16 through the opening 17.

The rejector fan is carried at the lower end 50 portion of the shaft 22, to which is keyed a hub 23 having an outwardly projecting annular flange 23a constituting a suitable shelf or support for a rejector fan structure consisting essentially of a rotary cage of vanes adapted to sweep an annular space in the separating chamber below

its outlet opening and thereby to cast from the particle-laden air stream as it passes to said opening the oversized particles present therein. The rejector fan structure comprises a lower annular plate 24 whose inner marginal portion is fixed, as by bolts 25, to the flange 23a. It comprises further an annular series of spaced blades or vanes 26 and an upper annular plate 27 arranged immediately about the lower end of the flange 9a and slightly below the inner marginal edge 16a of the top cover 16. The blades 26 extend edgewise from the lower plate 24 to the upper plate 27 and are secured to these plates, as by being welded thereto. It is preferable that these blades 26, whose outer and inner ends terminate on substantially concentric cylindrical surfaces, extend non-radially between such surfaces, as appears best in Fig. 5, so as to define therebetween a succession of non-radial ducts through which the particle-laden stream of air passes. While thus passing through these ducts, the stream of air undergoes such batting and centrifugal action by the rapidly rotating blades 26 as tend to cast out of the stream the oversized or relatively coarse particles. The blades 26 may be of any suitable width. However, when they are stationed at such pronounced angularity relative to the radii of the vertical axis of the shaft 22, as is illustrated in Fig. 5, sufficient batting action is realized therefrom even when their inner edges terminate no farther inwardly than the flange 9a, thereby creating a substantial open cylindrical space or region 3 immediately below the opening 17 in the separating chamber under the suctional or up-draft force of the main fan 19. It is thus seen that as the particle-laden stream of air enters the annular zone described by the rotating rejector fan blades 26 immediately below and around the lower end of the flange 9a, the particles are subjected to the vigorous batting or colliding action of the rapidly moving surfaces of such blades, in consequence of which the undesirably large or oversized particles are thrown out of suspension from the stream and are caused to settle as tailings at the lower end of the separating chamber.

Escape or leakage of particles through the clearance between the inner marginal edge 16a of the cover 16 and the flange 9a is obviated, in accordance with the present invention, by placing such clearance under a suctional current induced by the main fan. Thus, as illustrated in Fig. 2, such clearance is partitioned by a collar 29 which may be fixed in upstanding position at the inner marginal portion of the upper annular baffle 27, into two channels, one of which 30 communicates directly with the central suctional zone 3 below the main fan and the other 31 of which communicates with the suctional space immediately above and outside of the rejector-fan ducts or intake openings. There is thus no tendency whatever for unselected or coarse particles to escape from the separating chamber into the outlet opening 17; and all material leaving the outlet opening 17 has necessarily undergone the selective action of the rejector fan.

The air stream carrying the selected or desired particulate material in suspension therein may be discharged from the main fan chamber 18 by way of an outlet conduit 36 leading tangentially into a standard centrifugal collector 37, from which the air stream may be returned by way of a conduit 38 to the air-inlet 14 at the lower end of the casing 10. The size of outlet

in the conduit 36 is preferably controlled by a gate or valve 7, which thus enables regulation of the volume of the air stream passing through the rejector fan and, accordingly, the fineness of particle size in the selected or classified product. The selected product in the collector 37 may be discharged, as desired, through a discharge door 39 at its lower end.

The modified form of rejector fan shown in Fig. 3 is characterized by an upper annular baffle plate 40 of much larger diameter than that of the lower annular baffle plate 24. Indeed, the outer marginal edge of the plate 40 may occur slightly beyond the outer edges of the main fan blades 19a so that relatively narrow fan blades or ribs 41 may be mounted on the plate 40 to clear just under the cover and extend radially outwardly even beyond the outermost edges of the main fan blades 19a and thus create locally a clearance region 42 under greater suction than that prevailing at the center region 3 of the rejector fan subject to the influence of the main fan. The clearance region 42 may, as illustrated, communicate with the center region 3 of the rejector fan by way of a clearance 43 between the inner marginal edge of the baffle plate 40 and the lower margin of the flange 9a, wherefore, there will be during the operation of the rejector fan a constant flow or suctional drag of a thin layer of air next to the flange 9a past the clearances 9a and 42 and into the separating chamber. In short, the effect is to recirculate or bleed back in an air current to the separating chamber a small portion of the already selected particulate material by way of fine channels provided between the upper end portion of the rejector fan and the separating chamber outlet 17.

The rejector fan structure shown in Fig. 4 is similar to that of Fig. 2, excepting that there is no collar upstanding from the upper annular baffle plate 27 of the rejector fan and further that the top cover 16 of the separating chamber is turned downwardly at its inner margin to present a flange 16a encompassing the flange 9a and defining therewith an annular air duct 44 clearing the upper face of the upper baffle plate 27 and leading on one side by way of a clearance 45 to the separating chamber outlet 17 and on the other side by way of another clearance 46 to the separating chamber itself. It is thus seen that air from the outside atmosphere is constantly bled through the annular duct 44 past a clearance between the upper end portion of the rejector fan and the top of the separating chamber and thence into the separating chamber and also into its outlet opening leading to the main fan chamber, thereby maintaining the desired directionality of flow of all particulate material from the separating chamber to the zone of action of the rejector fan.

The shaft 22 may, as shown in Fig. 1, continue upwardly from the main fan chamber 18 through a stuffing box 32 formed in the base 33 of a yoke 34 in whose upper end portion 34a the shaft may be journaled for rotation and between whose upper end portion 34a and the base 33 the shaft may carry a driving pulley 35 suitably fixed thereto. The bottom portion 9 of the main fan chamber 18 may be arranged at slightly spaced relationship above the top cover 16 of the separating chamber 4; and such bottom portion 9 and top cover 16 may be interconnected by bolts 47 or in any other suitable manner. The feeding of particulate raw material into the separating chamber, the discharge of tailings or

rejected particles therefrom, and the discharge of collected particulate material from the collector 37 may be effected in such manner as to avoid the introduction or discharge of any substantial volume of air from the system. Again, excess air, such as is bled into the system, may be relieved from a suitable point in the system, say, from a point 38a in the air-return duct 38, into a suitable filter collector. It is possible also to use the air separator hereof in a so-called open-circuit system, in which case all the air from the collector 37 may be filtered prior to discharge into the atmosphere and atmospheric air may be drawn into the intake or lower end of the air separator.

It should be understood that various further modifications are possible in the air separator hereof and/or in the auxiliary equipment of the system in which such separator is used while falling within the spirit and scope of the present invention as defined by the appended claims.

I claim:

1. An air-separating system comprising a separating chamber having an upper end cover plate, means for delivering particulate material into said chamber, said chamber having an air inlet for delivering a stream of air thereinto at a region to cause suspension in said stream of said particulate material and having also an air outlet in said upper end cover plate, an air-suction chamber arranged above said separating chamber and comprising a bottom opening encompassed by an annular flange projecting downwardly into said air outlet, a rotary rejector fan stationed inside of said separating chamber adjacent to said air outlet, said fan comprising an annular upper end baffle plate arranged at a clearance about said annular flange and below said cover plate, the central opening in said baffle plate being in communication with said air outlet, said fan comprising also an annular series of fan blades defining ducts for leading the particle-laden stream of air inwardly from said chamber to said central plate opening and said air outlet, and means for rotating said rejector fan and thereby causing said blades to cast out oversized particles from said stream of air, said cover plate containing an opening substantially surrounding said annular flange and said air outlet, said clearance communicating with the atmosphere through said last-named opening to permit atmospheric air to be drawn therethrough in a direction into the separating chamber and also in a direction into said air outlet.

2. An air-separating system comprising a separating chamber having an upper end cover plate, means for delivering particulate material into said chamber, said chamber having an air inlet for delivering a stream of air thereinto at a region to cause suspension in said stream of said particulate material and having also an air outlet in said upper end cover plate, a main fan chamber arranged above said separating chamber and comprising a bottom opening encompassed by an annular flange projecting downwardly into said air outlet, a rotary main fan in said main-fan chamber, a rotary rejector fan stationed inside of said separating chamber adjacent to said air outlet, a single shaft on which both said rotary main fan and said rejector fan are carried, 70 said shaft extending through said main-fan chamber and projecting downwardly through said air outlet into said separating chamber, said rejector fan comprising an annular upper end baffle arranged at a clearance about said annu-

lar flange and below said cover plate, the central opening in said baffle plate being in communication with said air outlet, said rejector fan comprising also an annular series of fan blades defining ducts for leading the particle-laden stream of air inwardly from said separating chamber to said central plate opening and said air outlet and thence into said main-fan chamber, and means for rotating said shaft and thereby causing said stream of particle-laden air to be drawn upwardly from said separating chamber through said rejector fan and into said main-fan chamber and thereby also causing said rejector fan blades to cast out oversized particles from said stream of air, said cover plate containing an opening substantially surrounding said annular flange and said air outlet, said clearance communicating with the atmosphere through said last-named opening to permit atmospheric air to be drawn therethrough into the separating chamber and also into said air outlet.

3. An air separator comprising a separating chamber, a cover plate for said chamber, said cover plate having an outlet through which is drawn from said chamber a stream of air carrying particles of desired fineness, a main-fan chamber arranged above said separating chamber and containing a main fan for drawing said stream of air out through said outlet into said main-fan chamber, and a rejector fan within said separating chamber and adjacent to said outlet, said fan consisting essentially of a rotary cage of vanes adapted to sweep an annular space in said chamber below said outlet and thereby to cast from said stream oversized particles, said cage comprising a baffle plate arranged at a clearance adjacent to said cover plate and containing an opening substantially surrounding said outlet and in communication with said outlet, said clearance communicating with the atmosphere through said opening and said main fan serving additionally as means for inducing flow of atmospheric air through said opening and thence through said clearance in a direction into the separating chamber while said entire stream of air carrying particles is passing into the space swept by said vanes and thence through said outlet into said main-fan chamber.

4. An air separator comprising a separating chamber, a cover plate for said chamber, said cover plate having an outlet through which is drawn from said chamber a stream of air carrying particles of desired fineness, a suction chamber arranged above said separating chamber and containing suction means for drawing said stream of air out through said outlet into said main-fan chamber, and a rejector fan within said separating chamber and adjacent to said outlet, said fan consisting essentially of a rotary cage of vanes adapted to sweep an annular space in said chamber below said outlet and thereby to cast from said stream oversized particles, said cage comprising a baffle plate arranged at a clearance adjacent to said cover plate and containing an opening substantially surrounding said outlet and in communication with said outlet, said clearance communicating with the atmosphere through said opening and said suction means serving additionally as means for inducing flow of atmospheric air through said opening and thence through said clearance in a direction into the separating chamber while said entire stream of air carrying particles is passing into the space swept by said vanes and thence through said outlet into said suction chamber.

5. An air separator comprising a separating chamber, a cover plate for said chamber, said cover plate having an outlet through which is drawn from said chamber a stream of air carrying particles of desired fineness, a rejector fan within said separating chamber and adjacent to said outlet, said fan consisting essentially of a rotary cage of vanes adapted to sweep an annular space in said chamber below said outlet and thereby to cast from said stream oversized particles, said cage comprising a baffle plate arranged at a clearance adjacent to said cover plate and containing an opening substantially surrounding said outlet and in communication with said outlet, said clearance communicating with the atmosphere through said opening, and means for inducing flow of atmospheric air through said opening and thence through said clearance in a direction into the separating chamber while said entire stream of air carrying particles is passing into the space swept by said vanes and thence through said outlet.

6. An air separator comprising a separating chamber having an upper end cover plate, means for delivering particulate material into said chamber, said chamber having an air inlet for

delivering a stream of air thereinto at a region to cause suspension in said stream of said particulate material and having also an air outlet in said upper end cover plate, a rotary rejector fan 5 stationed inside of said chamber adjacent to said air outlet, said fan comprising an annular upper end baffle plate arranged at a clearance below said cover plate and with its central opening in communication with said air outlet and comprising also an annular series of fan blades defining ducts for leading the entire particle-laden stream of air inwardly from said chamber to said central plate opening and thence through said air outlet, said cover plate containing an opening substantially surrounding said air outlet, said clearance communicating with the atmosphere through said last-named opening, means for rotating said rejector fan and thereby causing said blades to cast out oversized particles from said stream of air, and means for inducing air to stream in a direction into the separating chamber through said last-named opening and thence through said clearance between said annular upper-end baffle plate and said cover plate.

20 25 THOMAS J. STURTEVANT.
